UNITED STATES PATENT OFFICE.

CHARLES L. HUSTON, OF COATESVILLE, PENNSYLVANIA, ASSIGNOR TO JACOBS-SHUPERT U. S. FIRE BOX COMPANY, OF COATESVILLE, PENNSYLVANIA, A CORPORATION OF PENNSYLVANIA.

BOILER-FIRE-BOX CONSTRUCTION.

1,012,358.

Specification of Letters Patent.

Patented Dec. 19, 1911.

Application filed September 26, 1911. Serial No. 651,345.

To all whom it may concern:

Be it known that I, CHARLES L. HUSTON, a citizen of the United States, residing in Coatesville, county of Chester, State of Pennsylvania, have invented certain Improvements in Boiler - Fire - Box Construction, of which the following is a specification.

My invention relates to certain improvements in the construction of fire boxes, especially the fire boxes of boilers of the locomotive type.

The object of my invention is to construct the fire box so that the joint between the mud ring and the inner plates of the fire box will be substantial and readily calked.

In the accompanying drawings:—Figure 1, is a transverse sectional view of a locomotive boiler fire box illustrating my improvement; Fig. 2, is a side view of the inner lining of the fire box; Fig. 3, is a sectional elevation on the line *a—a*, Fig. 4; Fig. 4, is a sectional plan view on the line *b—b*, Fig. 3; Fig. 5, is a sectional view on the line *c—c*, Fig. 3; Fig. 6, is a sectional view on the line *d—d*, Fig. 3; Fig. 7, is a detached side view of the lower portion of one of the plates of the inner fire box casing; Fig. 8, is a side view of one of my improved coupling plates; Fig. 9, is an edge view of the plate illustrated in Fig. 8; and Fig. 10, is a perspective view of the plate.

My invention relates particularly to the type of fire boxes made of a plurality of sections, one example of which is shown in the patent granted to H. W. Jacobs and F. W. Shupert, No. 917,172, dated April 6th, 1909. A fire box of this construction consists of two series of U-shaped plates connected together by stay plates. The U-shaped plates are in the form of channels having a body portion and flanges.

In the present instance the space between the inner and outer shells is greater above the crown than at each side, although this portion may be varied without departing from the essential features of the invention. Each outer section consists of a body 1 having flanges 2, and each inner section has a body 4 having flanges 5. The two sets of plates are connected by stay plates 3 which are secured to the flanges of the other plates by rivets or other fastening means.

The mud ring 6 is located between the

lower ends of the inner and outer plates and this mud ring is firmly secured to both the inner and outer plates by rivets or other suitable fastenings. The outer plates are made in the ordinary manner and in this type of boiler the plates terminate in the full width of the lower end of the mud rings and secured to the ring by rivets 7. The lower ends of the inner plates 4 are shaped as illustrated in Figs. 2 and 7; being cut away at each side and beveled to form a tongue 8. The edges of the plates terminate at a point above the mud ring, while the tongue 8 is secured to the mud ring by the rivets 7.

Heretofore the inner plates were elaborately shaped to make the joint between the plates and the mud ring water and steam tight, and to give the plates the necessary strength at this vital point of the boiler. I simplify the construction of the plates by securing to said plates a coupling plate 9, shown clearly in Figs. 8, 9 and 10, each coupling plate reinforcing the inner plates 4, as well as making simple and effective joints between the said inner plates and the mud ring. This coupling plate 9 is shaped as shown in Fig. 8, and has a series of rivet holes which align with the rivet holes in the plate and the mud ring. Rivets 10 pass through the holes of the coupling plate and the inner plates 4, while the rivets 7 pass through not only the holes in the mud ring and outer plates, but also through the holes in the inner plates and the coupling plates, making a very substantial and tight joint. The coupling plate 9 has a projecting socket 11, which is U-shaped and extends up on each side of the flanges 5 of the inner plates 4, and a rivet 12 passes through the holes in the walls of the socket member and through a hole in the flanges 5, as well as through a hole in the stay plate 3. The rivets 13 secure the stay plates to the flanges 5 of the plates 4.

It will be noticed that the edges 14 of each coupling plate abut one against another and the height of the plate at this point is equal to the height of the mud ring, so that the joint between the mud ring and these several coupling plates is perfectly rigid and is closed by calking, while the joint between the coupling plates and the plates 4 is calked on the lines *x*

and y , Fig. 3. In the event of leakage at any of these points, the joints y can be readily re-calked without dismantling the structure.

5 By the above construction, the inner fire box plates are reinforced at the point where strength is most desirable and the plates can be more readily assembled than in a construction where the joint is made
10 entirely by the overlapping of the inner plates.

By making the separate plates with U-shaped pockets, I am enabled to calk the fire box lining from the fire side and force
15 the metal of the stay plates into the pockets, making a very tight joint.

By making the separate coupling plates as shown I am enabled to simplify the construction of the fire box and at the same
20 time am enabled to make the pieces in large quantities at a very reasonable cost, thus reducing the cost of the boiler and insuring the perfect calking of the fire box at the mud ring.

25 While I have shown my invention as applied to a fire box having inner and outer sets of channel plates, it will be understood that the invention resides wholly in the construction of the fire box lining, and the
30 outer wall of the boiler may be made of plain sheets if found desirable.

I claim:—

1. The combination in a fire box, of flanged fire box lining plates; a mud ring
35 and coupling plates at the junction of the lining plates with the mud ring; and secured to both the mud ring and to the said lining plates.

2. The combination in a fire box, of a
40 series of lining plates; a mud ring to which the lower ends of the said plates are secured; coupling plates having their edges abutting at the side of the mud ring; with means for securing the said coupling plates
45 to both the mud ring and the lining plates.

3. The combination in a fire box, of a series of flanged lining plates; a mud ring to which the lower edges of the said lining plates are secured; and coupling plates
50 mounted between the lining plates and the mud ring.

4. The combination in a fire box, of a series of flanged lining plates; a mud ring to which the lower edges of the said lining plates are secured, and coupling plates
55

mounted between the lining plates and the mud ring; said coupling plates having sockets for the reception of the lower ends of the flanges of the lining plates.

5. The combination of a fire box, flanged fire box lining plates having downwardly extending tongues, a mud ring, stay plates mounted between the flanges of the first mentioned plates, and coupling plates secured to the mud ring and to the lining plates, and having pockets for the reception of the flanges of the lining plates and the edge of the stay plates.

6. The combination in a fire box, of inner lining plates inclosing the fire box; outer plates forming the shell of the boiler and extending over the lining plates; a mud ring to which both the inner and outer plates are secured; the outer plates having external flanges; the inner lining plates
75 having flanges extending into the space between the inner and outer plates; stay plates mounted between the flanges of the said plates and extending from one series of plates to the other; a series of coupling
80 plates mounted between the inner lining plates and the mud ring; and having sockets projecting into the space between the inner and outer plates; the walls of the said sockets extending on each side of the lower ends
85 of the flanges of the inner lining plates; with means for securing the several plates together.

7. A boiler having a fire box therein, consisting of a series of outer flanged plates
90 forming the shell of the boiler and inner flanged plates forming the lining of the fire box; a mud ring to which both sets of plates are secured; the flanges of the inner plates projecting into the space between the
95 inner and outer plates and terminating short of the mud ring; with coupling plates below the ends of the flanges and located between the mud drum and the inner lining plates; said coupling plates abutting each
100 other and secured to both the mud drum and said lining plates.

In testimony whereof, I have signed my name to this specification, in the presence of two subscribing witnesses.

CHARLES L. HUSTON.
